UNITED STATES PATENT OFFICE.

JAMES D. CONNELL, OF NEW ORLEANS, LOUISIANA.

SPARK-ARRESTER.

SPECIFICATION forming part of Letters Patent No. 339,268, dated April 6, 1886.

Application filed December 26, 1885. Serial No. 186,698. (No model.)

To all whom it may concern:

Be it known that I, JAMES D. CONNELL, a citizen of the United States, and a resident of the city of New Orleans, in the parish of Orleans and State of Louisiana, have invented a new and useful Improvement in Spark-Arresters for Locomotives, of which the following is a specification.

My invention relates to spark-arresters for locomotives which have a short smoke-box; and the objects of my invention are, first, to afford facilities by which locomotives equipped with a short smoke-box can be provided with an effective spark-arrester without extending 10 the smoke-box; second, to provide a means by which locomotives having a short smoke-box can be equipped with a straight sheet-iron stack without extending the smoke-box, which replaces a heavy cast-iron diamond stack and 15 materially reducing the weight of front of engine resting on engine-trucks, as also reduces the cost of construction; third, to afford facilities by which the combustion in locomotives equipped with a short smoke-box is materially improved, consequently the consumption 20 of fuel is reduced, which fact is substantially and unequivocally demonstrated by the experiments and comparisons I have made; fourth, to afford facilities by which no cinders 25 can accumulate in the smoke-box, rendering any devices for daily cleaning unnecessary; fifth, to provide a means by which the openings of exhaust-nozzles can be reduced or enlarged at pleasure; sixth, to afford facilities by 30 which a locomotive having a short box can be equipped with a most effective spark-arrester, which improves the combustion with but nominal expense, as also reduces the weight on front 35 end of engine; seventh, to provide a means by which all the parts of my device can be taken 40 out and replaced with ease and dispatch. I attain these objects by the mechanism illustrated in the accompanying drawings, in which—

Figure 1 is an end view of a locomotive 45 equipped with my device, with the front door of smoke-box removed; and Fig. 2 is a longitudinal section through center of smoke-box. Fig. 3 is a detail of exhaust-nozzles on an enlarged scale.

Similar letters refer to similar parts throughout the several views.

The steam-pipes S, connecting the dry-pipe

D and steam-ports P of cylinder, are shaped to be placed against the sides of smoke-box, as shown. A baffling-plate, B, placed on an angle, as shown, is secured by the angle-bar *a* to the front tube-sheet, *t*, of boiler. This baffling-plate B is constructed in two sections and secured together by bolts placed in the slots *s*, so that the distance from bottom of baffling-plate 55 to bottom of smoke-box can be regulated as may be desired. The wire-netting *N* is placed as shown on the drawings, it being secured by the angle-iron *i* to the baffling-plate B, and by the angle-iron *o* to the sheet-iron cover *c*. The 60 sheet-iron cover *c* is secured to the inside of front frame of smoke-box, as shown, and has a hand-hole, *h*, in same to enable the workmen to secure nuts, &c., in erecting the device, as also to alter size of exhaust-nozzles E. The 65 exhaust-nozzles E are made of wrought-iron tubing, to economize space and weight, and are secured by the set-screw *e* to the casting *g*, which is secured to top of exhaust-ports X of cylinder. The set-screw *e* fits into a recess, *m*, 70 Fig. 3, turned in the pipe or exhaust-nozzle E, to keep same in position.

The netting *N* is secured around the exhaust-pipes E by the plate *p*. The netting *N* being of sufficient fineness to prevent large cinders 75 from passing same, these large cinders are drawn against the netting *N* with sufficient force to break them up, when they pass through same and out of stack in fine particles.

A bushing, *b*, is placed in top end of the exhaust-nozzles E, and is secured by the set-screw *n*, fitting in the recess *r*, turned in the bushing *b*, as shown. The internal diameter of this bushing *b* can be of any size desired, and the size of opening from exhaust-nozzles can 85 be changed, when desired, by changing this bushing, which operation can be easily and quickly performed by means of the set-screw *r* and hand-hole *h*, the bottom edge of pipes E and bushing *b* being beveled, as shown, to 90 reduce friction.

H represents a straight sheet-iron stack.

T represents the tubes in the boiler.

Actual use of the device and comparison of the results of same with the same engine before 95 being equipped has demonstrated the following facts: The engine equipped with this device steams very much easier and produces improved combustion, which is demonstrated

by the saving of at least twenty-five one-hundredths in fuel, and the engine throws no sparks. No cinders collect in front smoke-box, which never requires cleaning out.

5 My device can be placed in any short smoke-box without requiring any change of steam-pipes or other parts except the heavy cast-iron exhaust-nozzles, which are replaced by light wrought-iron pipes.

10 Having thus described the construction and advantages of my improved spark-arrester for locomotives equipped with short smoke-boxes, I claim as new and desire to secure by Letters Patent—

15 1. In a spark-arrester for locomotives, the combination of a short smoke-box with the baffling-plates B, secured by angle iron *a* to front tube-sheet, *t*, of boiler, and constructed in

two sections and secured together by bolts working in slots *s*, wire-netting N, secured to 20 angle-irons *i* and *o*, the cover C, provided with the hand-hole *h*, and the exhaust-nozzles E, constructed of wrought-iron pipe, provided with casting *g*, set-screw *e*, plate *p*, bushing *b*, set-screw *n*, and recesses *r* and *m*, all substantially as set forth, and for the purpose specified. 25

2. In a spark-arrester for locomotives, the wrought-iron exhaust-nozzles E, secured to casting *g* by set-screw *e*, and provided with recess *m*, and bushing *b*, set-screw *n*, and recess 30 *r*, all substantially as set forth.

J. D. CONNELL.
